(57) **CLAIM**

The ornamental design for an air pipe connector, as shown and described.

DESCRIPTION

FIG. 1 is a top perspective view of an air pipe connector, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the air pipe connector in an alternate configuration with a different dash-dash broken lines;

FIG. 10 is a top perspective view of the air pipe connector in an alternate configuration with a different dash-dash broken lines; and,

FIG. 11 is a partial enlargement of FIG. 2.

The broken lines in the drawings illustrate the portions of the air pipe connector, which form no part of the claimed design. The dot-dash broken lines encircling portions of the air pipe connector in FIG. 2 and illustrated in enlarged views in FIG. 11 form no part of the claimed design.
